UNITED STATES PATENT OFFICE.

MARTIN KELLOGG PASCO, OF NEW BRITAIN, CONNECTICUT, ASSIGNOR TO AMERICAN HOSIERY COMPANY, OF NEW BRITAIN, CONNECTICUT, A CORPORATION.

UNDERGARMENT.

1,246,151.

Specification of Letters Patent.

Patented Nov. 13, 1917.

Application filed August 21, 1916. Serial No. 116,052.

To all whom it may concern:

Be it known that I, MARTIN KELLOGG PASCO, a citizen of the United States, residing at New Britain, in the county of Hartford, State of Connecticut, have invented certain new and useful Improvements in Undergarments, of which the following is a specification.

My invention relates to improvements in under-garments, of the type comprising in a unitary structure an upper bust portion and a lower leg portion, adapted particularly for women's wear, and in which the bust portion is made of knitted fabric and the leg portion of woven fabric, and the object of my improvement is to provide a special form for the junction of the bust portion and leg portion, adjacent the waist line or lower body portion by means of extensions of the material of the bust portion, forming a yielding structure for the said lower body portion due to the elasticity of the material of the bust portion, whereby a garment is provided that may be a good fit for all parts of the bust and body portions and without the use of a slit and buttons and button-holes for the lower body portion.

In the accompanying drawing:

Figure 1 is a front elevation of my improved under-garment.

Fig. 2 is a rear elevation of the same.

Fig. 3 is a front elevation on an enlarged scale of a portion of Fig. 1.

Fig. 4 is a rear elevation of the same.

Fig. 5 is a front elevation on the same scale as Fig. 1 of a modification.

My improved under-garment comprises a unitary garment having an upper bust portion 10 that is formed of knitted fabric and a lower leg portion 11 of woven fabric, the said portions being united at the waist line and lower body portions in a special manner.

The bust portion 10 is made complete and unbroken and may be provided with draw strings 12 at the extreme upper edge.

The leg portion 11 is made up of separate leg members 13 that at the rear are joined together at the middle of the waist line only, as shown at 14, the portions below the waist line being disconnected and normally overlapping, and the said leg members are each joined to the bust portion 10 at the rear along the waist line on each side of the junction 14 for an appreciable distance, as shown

at 15, the lateral ends of the waist line junctions 15 being indicated at 16.

At the front the leg members 13 are similarly joined to the bust portion 10 along the waist line for an appreciable distance as shown at 17, the lateral ends of the waist line junctions 17 being indicated at 18, and they have overlapping portions 19 adjacent the middle, extending downwardly from the waist line 16, that are joined by stitching 20 for a short distance, as shown, the portions below the said stitching 20 being free.

The parts of the waist line between the terminal points 16 and 18 on each side are filled in by extensions 21 of the material of the bust portion 10, the said extensions 21 being of appreciable width at the waist line, and extending downwardly as shown in V-shape over the hip portion, the apex 22 being substantially as far below the waist line as the stitching 20.

As described, the junction of the knitted material of the bust portion 10, and the woven material of the leg portion 11 extends between the points 18 at the middle of the front, extends downwardly at an angle from the points 18 to the points 22 at the sides, extends upwardly at an angle from the said points 22 at the sides to the points 16 at the rear, and extends between the said points 16 at the middle in the rear, and the same defines the bounds adjacent the waist line and lower body portion of the yielding material of the bust portion and the relatively rigid and non-yielding structure of the leg portion 11, due to the woven fabric material of which the said leg portion is formed.

Thus the body part of the leg portion is adapted to open out adjacent the hips in slipping the garment on and off and the garment can be drawn on from below, notwithstanding the relatively large hip structure of the wearer.

The yielding character of the V-shaped extension 21 permits of the essentially free opening of the junction portion described, in slipping the garment on and off as described.

In the garment shown in Fig. 5 a slotted structure is shown for the upper part of the bust portion 10^a having a set 12^a of buttons and button holes in lieu of the draw string 12.

It is understood that instead of the V-

shaped extension 21 of the material of the bust-portion 10 extensions of other form may be used and also that such extensions may be provided at other positions than at 5 the sides as shown.

Also other departures from the details shown may be made within the spirit of my invention.

For instance, the junction of the knitted 10 upper portion and the woven lower portion may be made without sections that are straight and parallel to the waist line and in lieu thereof having a wavy or serrated form, comprising additional extensions of the one 15 material fitting into recesses in the other.

In such case the entire junction of the two materials would be made up of two 20 similar serrated edges joined together. As described, the bust portion 10 corresponds to what is termed a vest structure, and the leg 25 portion 11 corresponds to a drawer structure, the two structures meeting at the waist line, and extensions of the material of the vest structure are provided and inserted at and below the waist line of sufficient extent 30 to provide a yielding character for the waist line portion, so that the garment can be slipped on and off readily without the provision of buttons and button-holes and the 35 like, and notwithstanding the fact that the waist portion is appreciably reduced relatively to the adjacent parts of the vest and drawer structures.

I claim as my invention:—

35 1. An under-garment comprising a vest structure of knitted fabric at the upper end, a drawer structure of woven fabric at the lower end, and a waist portion intermediate the said vest structure and drawer structure, the said waist portion being continuous 40 and unbroken, and appreciably reduced relatively to the adjacent portions of the

vest structure and drawer structure, and the said waist portion below the waist line being composed of the major portion of the upward extensions of the drawer structure at the front and back that meet the vest structure at the waist line and each of which extends an appreciable distance along the said waist line, and the remainder of the said 45 waist portion below the waist line being composed of integral downward extensions of vest structure that fill in between the extensions of the drawer structure and are of suitable size to impart a yielding character 50 to the part of the waist portion below the waist line, whereby the said part below the waist line will coöperate with the knitted portion above the waist line in yielding when in use. 60

2. An under-garment for women's wear composed of connected vest and drawers, and being fashion cut so as to provide a form fitting structure, having an enlarged bust portion and an enlarged hip portion 65 relatively to the intermediate waist portion, the said vest being made of yielding fabric, the said drawers being made generally of non-yielding fabric and being extended upwardly at the front and back of the waist 70 line, and being connected to the vest at the waist line, and the side portions of the waist portion being formed by material that is integral with the vest and extends continuously across the waist line, whereby a yielding character will be provided for the waist portion so that the waist portion can be opened out substantially to the size of the 75 said enlarged hip portion as the garment is slipped on and off.

MARTIN KELLOGG PASCO.
